M. M. LANG

CHECK WRITING FOUNTAIN PEN

Filed Aug. 29, 1921

UNITED STATES PATENT OFFICE.

MARTIN M. LANG, OF BROOKLYN, NEW YORK.

CHECK-WRITING FOUNTAIN PEN.

Application filed August 29, 1921. Serial No. 496,217.

To all whom it may concern:

Be it known that I, MARTIN M. LANG, a citizen and subject of Czechoslovakia (but having taken out his second papers with the intention of becoming a citizen of the United States), residing at New York city, borough of Brooklyn, in the county of Kings and State of New York, have invented a certain new and useful Check-Writing Fountain Pen, of which the following is a specification.

This invention relates to fountain pens, and is especially directed to a fountain pen adapted for use in the writing of checks in such manner as to effectually protect them against erasure or change. While the pen of this invention is especially intended for this use, it may be used for other purposes, such, for example, as the making of accurate copies and for other uses.

The pen of the present invention embodies a writing point associated with which is a plurality of cutting or perforating points or edges, which, as the writing operation proceeds, are alternately brought into engagement with and removed from contact with the paper on which the writing operation is being performed.

These perforating points or edges are inked and the writing point is also inked, so that as the person employs the writing point, to effect a writing operation, the perforating points or edges simultaneously operate to carry out an additional writing operation, which takes the form of inked perforations or knife cuts. The result of this operation is that the paper on which the writing occurs receives the markings of the writing point and also the inked perforations while, if desired, a second paper positioned below the first, will receive the cuts or perforations of the perforating points after they have passed through the first sheet, but not the markings of the writing point, which is not normally intended to pass through the first sheet.

The pen of the present invention is manipulated in a conventional way and the protective mechanism associated therewith is entirely automatic in its operation. It is compact and does not unduly encumber the pen nor render the same unsightly or bulky.

Features of the invention, other than those specified, will be apparent from the herein-

after detailed description and claims, when read in conjunction with the accompanying drawings.

The accompanying drawings illustrate one practical embodiment of the invention, but the construction therein shown, is to be understood as illustrative, only, and not as defining the limits of the invention.

Figure 1 is a central section of a pen embodying the present invention.

Figure 2 is a side elevation of the complete pen.

Figure 3 shows one end of the pen with the protecting cap removed; and,

Figure 4 is an enlarged detail section of a part of the construction shown in Figure 1.

Referring to the drawings, 5 designates an ink barrel or container adapted to form a reservoir for the ink supply to the writing point. In practice, this ink barrel may be that of a conventional fountain pen and may be provided at one end with the usual fountain pen nib, the present invention being associated with the other end of the barrel. It is thus shown in Figure 2 of the drawings.

In associating this invention with the barrel 5, one end of the barrel is reduced and exteriorly threaded as at 6 to receive a plug 7, which is interiorly threaded to screw upon the part 6. The other end of the plug is reduced and threaded as at 8 to receive the upper end of an interiorly threaded apron 8^a which is preferably tapered towards its open lower end.

Depending from the plug 7 is a rigid rod 9, the lower end of which is designated 9^a and constitutes the writing point. This rod is straight and mounted for longitudinal reciprocation thereon is a vibrator 10. This vibrator is in the form of a casing having a hollow interior and is guided at its top and bottom for reciprocation on the rod 9. Such movement is imparted to the vibrator by a link 11, the lower end of which is pivoted to the upper part of the vibrator and the upper end of which is pivoted to the long arm of the lever 12 fulcrumed at 13. The other arm of the lever 12 is pivoted to a rod 14, the lower end of which is adapted to be maintained by a compression spring 15 in engagement with the surface of a spherical ball 16. This spherical ball is mounted for rotation in a cup 17, which is rigid with a bracket 18. This bracket extends upwardly

to a screw plug 19 threaded into an orifice 20 in the base of the plug 7, and is provided above the plug 19 with a seat 21. The bracket 18 may conventionally be made circular in cross section and when so constructed, it is provided with feathers 22 which pass through the screw plug 19 in such manner as to permit vertical adjustment of the bracket 18, but to preclude rotation of said bracket 10 within the plug 19. The bracket 18 may conveniently be formed with a lug 23 providing a bearing for the rod 14, as clearly shown in Figure 1.

The spring 24 is coiled about the bracket 15 18, below its head 21 and above the screw plug 19 and normally tends to elevate the bracket, which tendency is opposed by a wedge 25 mounted for longitudinal adjustment radially of the plug 7 and adapted to 20 cooperate with a transverse slot 26 in the head 21. The wedge 25 is cut out at its after end to receive the ball shaped end 27 of an adjusting screw 28 threaded through a screw plug 29 and this threaded connection is preferably 25 a double or triple thread, so that relatively small angular adjustment of the adjusting screw 28 will effect a pronounced longitudinal travel of the screw, and a correspondingly pronounced degree of travel of 30 the wedge 25.

Positioned on the exterior of the plug 7 is a dial 30 immediately exterior of which is a locking plate 31 provided with turned down edges having projecting points adapted 35 to normally engage with small apertures formed in the dial 30. A spring 32 is positioned between the locking plate 31 and a head 33 of the adjusting screw and normally serves to force the projections of the locking 40 plate into the holes of the dial. The outer periphery of the dial may be graduated and the locking plate may have thereon a reading pointer, so that the proper adjustment may be had. In order that correct readings 45 may be obtained, the locking plate 31 is preferably secured to the adjusting screw 28 by a key 34, so that the locking plate turns with the adjusting screw.

When it is desired to operate the adjusting screw, the locking plate is manually retracted against the tension of the spring 32, whereupon the screw may be rotated to advance or retract the wedge 24 and permit the raising or lowering of the bracket 18 and 55 the ball 16 carried thereby. The reason for this adjustment is to regulate the throw of the vibrator 10 for reasons hereinafter manifest.

The ball 16 functions as a prime mover for 60 the vibrator and to this end, the surface of the ball is provided with small and relatively shallow indentations throughout its surface, so that when the ball is turned, the lower end of the rod 14 will alternately ride 65 into and out of these depressions and in so

doing will be reciprocated for the purpose of reciprocating the vibrator 10 through the lever 12 and link 11.

It will be noted that the arms of the lever 12 are of unequal length, so that the reciprocations of the rod 14 may be enlarged or amplified during their transmission to the vibrator 10.

The parts are so relatively positioned that if the writing part 9^a is caused to traverse a surface to be written upon, the ball 16 will also engage with said surface and will roll over the same during the writing operation. The lower end of the vibrator is reduced and extends downwardly about the rod 9 and its lower edge is sharpened to form a knife edge 35. This knife edge is preferably serrated, so as to produce perforating points which, during the operation of the device, are alternately brought, through reciprocation of the vibrator 10 into and out of engagement with the paper on which the writing is being carried out so that said points will perforate the paper.

Ink is supplied to the writing point 9^a and to the perforating points or knives 35 by means of a tube or duct 36, which extends through the plug 7, downwardly from the lower edge thereof, through the top of the vibrator 10 and through a collar or disc 37 positioned within the vibrator and fixed on the rod 9.

Secured to the disc 37 is one end of a spring 38, the other end of which is secured to an inking pad 39. The ink, flowing by gravity from the reservoir 5, is discharged from the lower end of the duct 36 and drips on the pad 29. As the vibrator is elevated it presses against the under side of the ink pad and squeezes ink out of the same, so that such ink may run down around the rod 9, writing point 9^a and simultaneously pass through small channels 40 and 41. These channels 40 and 41 are bored through the bottom of the vibrator. The channels 40 lead the ink downwardly between the rod 9 and the perforating points 35, while the channels 41 lead the ink downwardly over the outer faces of the perforating points 35. It will thus appear that the inking point, as well as the perforating points are simultaneously inked, each time the vibrator is operated, so that they are practically constantly supplied with writing fluid.

In employing the pen thus far described, 120 the barrel 5 is grasped in the usual manner and the point 9^a is employed for writing. While the writing operation is being carried out, however, the ball 16 rolls over the surface of the paper and in so doing reciprocates the vibrator 10, thereby causing the knife edges 35 to puncture or perforate the paper. Since the knife edges contain ink, the perforations are inked as they are made, thereby producing unalterable writing.

It will be apparent that through the adjustment of the wedge 25, the throw of the vibrator may be so regulated that the perforations made in the paper will extend just 5 through the paper and not be on the lower face thereof, though, in practice, it is feasible to so adjust the wedge that the perforations will be cut deeper and through one or more sheets of paper laid beneath the 10 paper on which the writing is being carried out. In this way, accurate copies may be obtained of the original, though, in the copies, the lines produced by the writing point 9^a on the original will not appear. 15 Through the manipulation of the wedge, the depth of cut may be adjusted, so that any number of copies may be made in the manner described.

When the mechanism is not in use, it may 20 be enclosed within a suitable protecting cap 42, as shown in Figure 2 and the closed end of this cap is reduced as at 43, so as to receive the conventional protecting cap 44, which normally serves to enclose the conventional writing point at the other end of the barrel.

The barrel 5 may be of self filling variety or the plug 7 may be removed to permit of filling of the pen, but, for convenience, 25 I preferably make the pen self filling. To this end, a piston 45 is operable interiorly of the barrel 5 and normally partakes of the position shown in Figure 1, so as to allow ink to flow around the outer edge of 30 the piston and supply the duct 36. A tubular rod 46 extends through the center of the plug 7 and through the center of the piston 45 and the inner end of this tube has an enlarged closed head 47. Interiorly 35 of the head 47, which is hollow, is a bowed leaf spring 49, the opposite ends of which are provided with plungers 49. The spring 48 is secured to the head 47 by a rivet 50 and the tension of the spring normally 40 draws the plungers 49 toward one another. Positioned within the bow of the spring 48 is a wedge 51 to which is secured a rod 52, which passes longitudinally through the tube 46 and is provided beyond the end of 45 the same with a knob 53.

When it is desired to fill the pen, the parts are brought into the position shown in Figure 1 and thereupon the knob 53 is grasped and tension applied thereto, so as to force 55 the wedge to expand the arms of the spring 48 and project the plungers 49 into an annular groove 54 in the piston 45. This having been accomplished, the wedge 51 is maintained in this position and the tube 46 is forced longitudinally so that the piston 45 will be forced to the opposite end of the ink reservoir for the purpose of exhausting the air therefrom. The conventional end 60 of the pen is next dipped into an ink well, whereupon the tube 46 is retracted, and

draws the piston 45 with it, thereby producing a partial vacuum in the reservoir into which the ink from the ink well flows. When the piston 45 has been fully retracted to the position of Figure 1, the knob 53 70 is released and pushed in to retract the wedge 51 and allow the plungers 49 to withdraw from the channel 54. This having been accomplished, the tube 46 and rod 52 are pushed all the way in by means of a 75 laterally projecting arm 55, which is adapted to traverse a slot 56 in the side of the apron 8^a and plug 7, as shown in Figure 3 and comes to rest in the position shown in Figure 2, where it will be out of the way, 80 though in convenient position to be withdrawn for subsequent filling operations.

The pen of the present invention has been described in its preferred, practical form as embodying an adjustable bracket 18 and self filling means. I wish it understood however that a very satisfactory pen results if the bracket is made rigid, i. e., without adjustment, and the self filling means omitted. The present invention is particularly directed to means associated with the writing point and brought into operation automatically by the act of writing to perforate the paper on which the writing is being carried on. It is preferred that the 95 perforations be inked, though the present invention is not restricted to this feature. I am aware that various modifications in structural detail, such as the substitution of equivalents, may be made without departing 100 from the spirit or scope of this invention which is as broadly novel as is commensurate with the appended claims.

Having thus fully described the invention, what I claim as new and desire to secure by Letters Patent is:

1. A device of the class described embodying a writing point, perforating means associated with the writing point, and means adapted to roll over the surface of the paper for operating the perforating means to effect the perforation of the paper while the writing operation is being carried out.

2. A device of the class described embodying a writing point, perforating means associated therewith, and means operable by the travel of the point over the surface of the paper for alternately bringing the perforating means into and out of engagement with the paper.

3. A device of the class described embodying a writing point, a vibrating member associated with the writing point and provided with perforating members, a prime mover adapted to be rolled over the paper during the movement of the writing point over the paper, and connections between the prime mover and the vibrator, whereby the movement of the writing point over the surface of the paper is accompanied by the 130

rolling of the prime mover over the surface of the paper and the consequent operation of the vibrator to effect a perforation of the paper.

- 5 4. A device of the class described embodying a writing point, a vibrator guided for reciprocation on the writing point and provided with perforating members, means for supplying ink to the writing point and the 10 perforating members, a ball, provided with surface depressions, adapted to roll over the surface of the paper, while the writing point is traversing said surface, means for supporting said ball for simple rotation, 15 an operating rod engaging with the surface of the ball and adapted to be reciprocated when the ball rotates, and operative connections between the rod and the vibrator to render the vibrator responsive to the reciprocations of the rod, whereby the passing of the writing point over the surface of the paper is accompanied by reciprocation of the vibrator and the perforation of the paper by the perforating members.
- 20 5. A device of the class described embodying a writing point, a vibrator guided for reciprocation on the writing point and provided with perforating members, means for

supplying ink to the writing point and the perforating members, a ball, provided with 30 surface depressions, adapted to roll over the surface of the paper, while the writing point is traversing said surface, means for supporting said ball for simple rotation, an operating rod engaging with the surface of 35 the ball and adapted to be reciprocated when the ball rotates, operative connections between the rod and the vibrator to render the vibrator responsive to the reciprocations of the rod, whereby the passing of the writing point over the surface of the paper is accompanied by reciprocation of the vibrator and the perforation of the paper by the perforating members, and means for varying the throw of the vibrator to regulate 40 the depth of the perforations.

- 25 6. A device of the class described embodying an ink reservoir, a perforating device mounted for reciprocation and adapted to be supplied with ink from the reservoir, 50 and means adapted to roll over the surface of the paper to cause reciprocation of the perforating device.

In testimony whereof I have signed the foregoing specification.

MARTIN M. LANG.
